ATTORNEY

UNITED STATES PATENT OFFICE.

THOMAS H. ROSS, OF BROOKLYN, NEW YORK, ASSIGNOR, BY MESNE ASSIGNMENTS, TO ARCAS BRASS AND IRON COMPANY, INC., OF NEW YORK, N. Y., A CORPORATION OF NEW YORK.

CAN OPENER.

Application filed May 9, 1923. Serial No. 637,685.

To all whom it may concern:

Be it known that I, THOMAS H. ROSS, a citizen of the United States, and resident of borough of Brooklyn, in the county of Kings and State of New York, have invented certain new and useful Improvements in Can Openers, of which the following is a specification.

This invention relates to can openers and my improvement is particularly devoted to the novel and economical construction of these devices to the end that they may be more efficient in service and durable in character.

Briefly expressed, my invention comprises a shank provided with a suitable handle and having a continuing blade which is curved in longitudinal section in order that it may conform approximately to the contour of the can wall at the inner surface thereof when cutting out the top.

The blade is offset from the shank, being connected therewith by a web that serves as a bearing to co-act with the top of the can wall as a fulcrum, and this web is provided with an inclined recess at its lower edge, to localize the device upon the can wall. Also extended out from the shank is a guide finger, which, being aligned with the shank, lies spaced from the blade in a parallel plane therewith, the extent of the space separating the blade and guide being sufficient to permit the guide to bear against the outer surface of the can wall while the blade is operating against the inner surface of said wall.

In this manner the blade is drawn snugly against the can wall and hence the top of the can is cut out close against the wall. By these means no jagged edge is produced in the can top in the opening operation.

Other features and advantages of my invention will hereinafter appear.

In the drawings:

Figure 1 is a plan view of my improved can opener.

Fig. 2 is an edge view thereof.

Fig. 3 is a top plan view of a can showing the opener in operation.

Fig. 4 is a view looking in the direction of the arrow 4 in Fig. 3; and

Fig. 5 is a section on the line 5—5 of Fig. 4.

In the figures, let 1 indicate the shank of my improved can opener, this being socketed in a handle 2, and having a longitudinal rib 3 formed therein to reinforce it. The shank is of flat material, as shown, and is broadened outwardly at 4, whence it continues into the bifurcations which respectively constitute the blade 5 and guide 6. The guide 6 is here shown in the form of straight, flat member, in continued alignment with the shank, but the blade 5, which is concavo-convex longitudinally, with its convex surface opposed to the edgewise plane of the guide, is offset from the portion 4 of the shank, to which it is connected by a web 7, the root of the web springing from the initial point 8 of bifurcation. Between that point 8 and the heel 9 of blade 5 I provide an inclined recess or depression 10 in the web, which serves as a seat or bearing to co-act with the top edge of the can wall that thus constitutes a fulcrum for the opener, the recess localizing the fulcrum and urging the convex surface of the blade against the inner surface of the can wall.

Also the guide finger 6, whose inner surface may be roughened or provided with gripping teeth 11, bearing against the outer surface of the can wall, thereby has the effect of drawing the blade against the can wall, and causing the incision in the can top to be made at the inner perimeter of the wall.

The blade 5 has a terminal point 12 to facilitate penetration of the can top, and is beveled in the direction of the plane occupied by the guide, to provide a cutting edge 13.

Variations within the spirit and scope of my invention are equally comprehended by the foregoing disclosure.

I claim:

A can opener having a bifurcated end forming a straight shank portion and a blade portion offset laterally from the shank portion, said portions terminating substantially

opposite each other and connected by a diagonally disposed web, said web having a fulcrum notch on its under side, the notch having two angularly disposed faces, one of which slopes upwardly from the portion of the web adjacent the shank to form a guide surface, and the other of which extends

downwardly from the first face to the back of the blade to form an abrupt shoulder.

Signed at borough of Manhattan, in the 10 city, county and State of New York, this 5th day of May A. D. 1923.

THOMAS H. ROSS.
